G. H. Davis

Attorney

UNITED STATES PATENT OFFICE.

OSCAR A. DOVER, OF GASTONIA, NORTH CAROLINA.

LUBRICATING MEANS FOR SPINNING-RINGS.

1,375,833.

Specification of Letters Patent. Patented Apr. 26, 1921.

Application filed June 28, 1920. Serial No. 392,399.

To all whom it may concern:

Be it known that I, OSCAR A. DOVER, a citizen of the United States, residing at Gastonia, in the county of Gaston and State 5 of North Carolina, have invented certain new and useful Improvements in Lubricating Means for Spinning-Rings, of which the following is a specification.

My invention relates to the twister frames 10 of spinning machines and more particularly to the construction of an improved spinning ring for use in connection therewith.

The object of the invention is to provide means for conveniently and effectively sup- 15 pplying oil to lubricate such spinning ring, so as to cause the traveler to run freely and smoothly thereon without undue friction.

More specifically, I contemplate providing the rings of existing machines with my im- 20 proved lubricating means, so that twister frames in common use may be equipped with my invention, without the necessity of buying new rings or parts of any kinds.

In order that my invention may be readily 25 understood, reference is had to the accompanying drawings, forming part of this specification and in which—

Figure 1 is a fragmentary plan view of a portion of a ring rail showing a spinning 30 ring thereon provided with my improved lubricating means;

Fig. 2 is a vertical section substantially on the line 2—2 of Fig. 1, and

Fig. 3 is an enlarged fragmentary section 35 on the same line.

Referring to the drawings in detail, 1 designates the usual ring rail on which the rings are supported. The ring itself, which is smooth and imperforate throughout, and 40 has a vertical outer wall, is designated by the reference numeral 5, and is provided with a peripheral flange 2 constituting a holder. This flange is formed with diamet- rically opposed slotted lugs 3, through which 45 set screws 4 pass. By means of these set screws the ring and flange may be adjust- ably secured to the ring rail.

6 designates the traveler which may be of any usual or desired form.

50 In the upper surface of the holder or flange 2, I form an annular oil receiving groove 7, which surrounds the ring 5, and at one or more points I provide ducts 8 extending downwardly from the groove 7

through the flange 2, to the lower side there- 55 of. As shown in Fig. 3, these ducts 8 are preferably inclined and terminate at their lower end adjacent the outer vertical wall of the ring 5.

By virtue of this construction, it will be 60 apparent that oil placed in the groove 7 will flow downwardly through the ducts 8 from whence it will find its way over and around the outer wall and lower edge of the ring 5. Such oil is uniformly distributed around 65 the ring by the movement of the traveler.

The ring 5 is usually constructed of har- 70 dened steel, while the flange or holder 2 may be formed of brass or the like, and it will be noted that with my improved con- struction, it is not necessary to bore or drill 75 through the ring itself in order to supply oil to the lower edge thereof, as in arrange- ments heretofore proposed, oil is delivered to the outer surface of the ring and finds its way downwardly along the same.

It will thus be seen that I have provided a simple and effective arrangement for dis- 80 tributing oil to spinning rings, my improve- ment being such that it can be readily ap- plied to existing rings now in use, and it is thought that the many advantages of my in- vention will be apparent without further discussion.

What I claim is:

1. The combination with an imperforate spinning ring, of a supporting member therefor, said member having in its upper face an annular oil groove surrounding the ring, and provided with ducts extending 90 through itself so as to conduct oil to the lower edge of said ring.

2. The combination with a spinning ring having a vertical outer wall, of a supporting member for said ring, said member having 95 in its upper face an annular oil groove and provided with ducts extending downwardly through itself and terminating adjacent the vertical wall of said ring, whereby oil is conducted from said groove to said ring, and 100 flows down and over the outer surface thereof.

In testimony whereof I affix my signature.

OSCAR A. DOVER.
